UNITED STATES PATENT OFFICE

ARMEN POTIGIAN, OF DAVENPORT, IOWA

CAN OPENER

Application filed September 19, 1928. Serial No. 306,870.

The present invention relates to improvements in can openers and is more particularly concerned with adjustable can openers which may be used for the opening of cans of various dimensions. Among the objects of this invention are to provide a can opener of the character indicated which will securely hold a can during the opening thereof; to provide a can opener which is adjustable for variations in diameter and length of can; to provide an implement of the character indicated which is rigid in construction and yet capable of being easily adjusted; and such further objects, advantages and capabilities as will hereafter appear and as are inherent in the construction disclosed herein. My invention further resides in the combination, construction and arrangement of parts illustrated in the accompanying drawings and, while I have shown therein what is now considered the preferred embodiment of this invention, I desire the same to be understood as illustrative only and not to be interpreted in a limiting sense.

In the drawings annexed hereto and forming a part hereof, Fig. 1 is a side elevation of a construction embodying my invention; Fig. 2 is an elevation at a right angle to the view shown in Fig. 1; Fig. 3 is a sectional plan of the construction shown in Fig. 1 taken substantially along the line 3—3 of said figure; Fig. 4 is a fragmentary cross section of the cutter arm and holding means, showing the cutting blade and a portion of its handle in elevation; Fig. 5 is a similar view of the centering point for perforating the can end and holding the can in position with relation to the other parts of the mechanism; Fig. 6 is a detached view of the centering point, partly in perspective.

Referring more in detail to the annexed drawings, numeral 1 denotes a base provided with a plurality of screw holes 2 by means of which the base can be secured to any suitable support such as a table. An upright 3 is preferably formed integral with the base and is provided with a plurality of perforations 4 which are screw threaded for the reception of the screw 5.

This latter is locked in place by means of the wing nut 6 or any equivalent device. If desired, this locking means may be dispensed with, though it is believed preferable to use the same. The threaded member 5 is provided with an elongated point 5a which is designed to perforate the side of a can 7 just below the rim 8 at the top thereof, as indicated in Fig. 1.

The upright member 3 is made in two sections, the upper of which is designated by the numeral 9, the two parts being held together by securing means 10 such as bolts and nuts. This adjustment makes it possible to adjust the height of the device for cans of various lengths. Pairs of holes 11 are provided to enable this adjustment to be accomplished. Horizontal adjustment of the screw 12 with relation with the upright 3, 9 is provided for by having a horizontal bracket 13 adjustably secured to the horizontal projection 14 of the upright member 9. A screw threaded block 15 is secured to the horizontal arm 13 to furnish sufficient bearing for the screw 12 which is adjustable in the block 15.

The screw 12 is provided at its lower end with a head 16, which latter has a slot 17 for the reception of the centering point 18. This centering point is shown most clearly in Fig. 6. While the flange 19 thereof may be formed integral with the body, as shown in Figs. 5 and 6, it is also possible to screw thread the body of the centering point and have a screw threaded washer mounted thereon to form a detachable flange instead of a rigid flange. This centering point also has a substantially rectangular elongated head 20 which fits tightly in the slot 17 in head 16. This head 20 is provided with a transverse opening 21 which may be caused to align with a corresponding transverse opening in the head 16. A pin or bolt 22 may pass through these openings and be secured therein to hold the centering point in the slot 17. The securing means may be a cotter pin 23 passed through the bolt 22, as shown in Fig. 5, or the bolt may be screw threaded and have a wing nut thereon.

A space or groove 24 is formed between the flange 19 and head 20 and the longitudinally slotted bar 25 is mounted in this space before the centering point is attached to the head 16. The bar may be moved longitudinally with respect to the centering point to get the cutting point 26 in the desired location with respect to the head of the can which is to be opened. This bar is loosely enough mounted so that it may be freely moved lengthwise and in an arc about the centering point.

Adjustably mounted on the bar 25, which is provided with an operating handle 28, is a carrier block 29 consisting of two members suitably secured together. The upper one, 30, is undercut on two opposite sides as shown in Fig. 4 to provide grooves in which the edges of the bar 25 may be received, as shown in this figure. These two blocks are secured together in any suitable manner, as by a plurality of screws not shown in the drawing. The cutter point 26 has a screw threaded shank 31 which is received in a screw threaded opening in block 29. A handle 32 has a screw threaded shank provided with two screw threaded sections 33 and 34, the latter of which is screwed into the upper section 30 of the block 29. This handle serves as means whereby the cutter point may be adjusted with relation to the bar 29 when it has been released. A bridge member 35 straddles the block 30 and has its edges in engagement with the upper surface of the bar 25. When the locking member 36 is screwed downwardly on the screw threaded section 33, it presses the bridge 35 against the bar 25 and holds the cutter point and its associated elements against longitudinal motion along the bar 25. When these parts have been adjusted to the desired location with relation to the bar 25, the locking member 36 is screwed down to lock them in position until such time as it is desired to again adjust them with relation to the bar.

Eyes 38 are formed on the edges of upright 3 and receive a securing pin 39 which also passes through an eye on one end of member 40 which is secured to and serves as a terminal for the ends of the bands 41. This member 40 is thus pivotally mounted with relation to the upright 3, being pivoted on the pin 39. A stop 42 limits the amount which this member may swing inwardly under tension during use. Member 40 has a pair of transferably perforated lugs 43 projecting therefrom. These extend through perforations 44 in the bands 41 and will hold the same adjusted to the size of the can, when a pin 45 has been inserted in the perforations through the lugs. When the can has been so adjusted that the center of the top thereof is beneath the point 18 and the bands 41 are drawn tightly against the same and secured in position as shown in Fig. 3,

the screw 46 is then turned in until its head 47 engages tightly against the can and presses it against the bands 41. A wing nut 48 may then be turned down on the screw 46, if desired, and will clamp the washer 49 against the bands to assist in holding them in adjusted position.

Projecting from one edge of member 1 is a bracket 50 on which is pivotally mounted a holding member 51 provided with a vertically extending flange 52. The other end of this holding member has a latch member 53 pivotally connected thereto which latch member is provided with notches 54 adapted to engage a pin 55 in the member 1 and serves to hold member 51 in adjusted positions. The purpose of this holding member is to engage the side of a can during the cutting operation and prevent the same from swinging laterally under the cutting pressure, thereby putting undue bending strains upon the bands 41.

The operation of this device will now be restated completely. Assuming the base 1 to be secured to a table or other suitable support, the bands 41 are loosened, if necessary, until the can which it is desired to open can be placed within the bands and underneath the point 18. This can will then be adjusted until it is centered with relation to the point. The screw 12 is then turned down until the point 18 perforates the can top and extends some distance within the can. The bands 41 are then drawn tightly about the can and the lugs 43 are caused to enter openings 44, the pin 45 then being inserted through the perforations in the lugs. The screw 46 is next screwed in until the head 47 engages the can tightly and then the wing nut 48 may be screwed up or not as desired. It is believed desirable to screw this up so that the washer 49 will assist in holding the bands 41 in adjusted position, as well as holding the screw tightly in place, though the latter function will be accomplished satisfactorily without the aid of the wing nut 48. The screw 5 is now turned in until the point 5a enters the top of the can just beneath the flange 8. The wing nut 6 may be tightened up or not, as desired. The member 51 is drawn over against the can and the appropriate notch 54 is caused to surround the pin 55 so that member 51 will be prevented from swinging about its pivotal connection with the extension 50. The cutting point 26 is then caused to cut into the can top, just inside the rim, the screw 12 being screwed down to accomplish this. By now grasping the handle 28 and swinging the same about its connection with the point 18, the knife 26 will be caused to cut through the metal of the can top, nearly severing the same from the can. The can can now be removed from the opener in an obvious manner and the contents removed therefrom.

Having now described my invention, I claim:

1. In a can holder, a base having an upright rising therefrom, means to hold the can rigidly with relation to the upright, and means connected with the upright to perforate the can adjacent its upper end and hold it against rotation relatively to the base.
- 10 2. A can holder comprising a base upon which the can to be opened is placed, said base being adapted to be secured to a suitable support and having an arm projecting laterally therefrom, the same being rigidly connected thereto, a flanged adjustable lever pivotally connected with said arm, said lever and base having co-operating means whereby the lever may be secured in adjusted positions to prevent lateral motion of a can with relation to the base, the body of 20 the lever supporting the can and the flange thereof arranged to furnish lateral support for the can.
- 25 3. A can holder comprising a base adapted to be secured to a suitable support, said base having an arm projecting laterally therefrom, a flanged adjustable lever pivotally connected with said arm, said lever and base having co-operating means whereby the lever may be secured in adjusted positions to prevent lateral motion of a can with 30 relation to the base, said base having an upright rising therefrom and said upright being provided at its lateral edges with eyes, a holding means pivotally connected with part of said eyes, a flexible, resilient band connected with said holding means and adapted to surround a can, said holding means having a stud projecting therefrom, said band being provided with perforations along its length to engage said stud and adjust the size of the opening within the band to the size of a can, means to lock the band in place on the stud, and means extending through the upright, said last 45 named means being adjustable to press the can against the band whereby the can will be tightly held.

In witness whereof, I hereunto subscribe my name to this specification.

ARMEN POTIGIAN.
